UNITED STATES PATENT OFFICE.

WILLIAM J. JEFFERS, OF COPAN, OKLAHOMA.

DRILLING RIG.

Application filed October 19, 1920. Serial No. 413,057.

To all whom it may concern:

Be it known that I, WILLIAM J. JEFFERS, a citizen of the United States, residing at Copan, in the county of Washington and State of Oklahoma, have invented certain new and useful Improvements in Drilling Rigs, of which the following is a specification, reference being had to the accompanying drawings.

10 This invention relates to improvements in drilling rigs.

An important object of the invention is to provide a device of this character in which the use of clutches is dispensed with.

15 A further object of the invention is to provide in a drilling rig a novel and efficient construction of spudding arm consisting of a series of link connections so constructed, that at the point of connection with the bit

20 holding cable of the drilling rig the spudding shoe has no movement at all upon the cable and consequently does not wear upon the same.

A still further object of the invention is 25 to provide a device of this character which may be readily controlled and operated by a single attendant.

Other objects and advantages of the invention will become apparent throughout 30 the course of the following description.

In the accompanying drawings, wherein for the purpose of illustration is shown a preferred embodiment of my invention, and wherein like reference characters designate 35 like parts throughout:

Figure 1 is a plan view of the well drilling rig constructed in accordance with my invention;

Figure 2 is a side elevation thereof;

40 Figure 3 is a section taken on the line 3—3 of Figure 1;

Figure 4 is a section taken on the line 4—4 of Figure 1;

45 Figure 5 is an enlarged detail view showing in solid lines the bull wheel in the neutral position, and in dotted lines the bull wheel in driving connection with the band wheel shaft;

Figure 6 is a side elevation showing the 50 mounting of this end of the bull wheel shaft;

Figure 7 is an end elevation thereof;

Figure 8 is a section taken on the line 8—8 of Figure 2, and

55 Figure 9 is a detail sectional view showing the sand wheel driving connection in driv-

ing position in full lines and neutral position in dotted lines.

Referring now more particularly to the drawings, the numeral 10 indicates a 60 substantially rectangular wheel-supported frame having mounted upon the forward end thereof a mast 11 consisting of upper and lower sections 12 and 13 pivotally connected, as at 14, so that the sections of the mast may be folded when the rig is being transported from place to place. When in use, the upper section of the mast is held in elevated position by braces 11^a secured to the upper section of the mast and to the 65 rear end of the frame 10.

Extending transversely of the frame 10 is a band wheel shaft 15, one end of the shaft projecting exteriorly of the frame and being provided thereon with a band wheel 16. The frame is provided forwardly thereof with a power plant of any suitable description, shown in the present instance as comprising an engine 17 to the shaft of which is secured a driving pulley 18 which 70 is connected with a band wheel 16 by a belt 19.

Extending transversely of the frame forward of the band wheel shaft 15 is a bull wheel shaft 20. The band wheel shaft 15 75 is provided adjacent one side of the frame with a friction drum 21 preferably provided upon its outer surface with a V-shaped friction face. Mounted upon the bull wheel shaft 20 is a bull wheel 22 having its periphery provided with a V-shaped groove adapted to coact with the friction face of the friction wheel or drum 21. Upon the opposite side of the bull wheel from the friction drum 21 is mounted a stationary brake 95 23. When in the neutral or normal position the bull wheel 22 is out of engagement with both the friction frame 21 and the brake 23.

The end of the bull wheel shaft 20 next 100 adjacent the bull wheel 22 has its bearing formed in a plate 24 eccentrically thereof. This plate 24 is rotatably mounted in and held in engagement with in any suitable manner a bracket 25 secured to the frame 10. Secured to and extending upwardly from the plate 24 is an arm 26 to the upper end of which is pivotally connected the rear end of the operating rod 27, the forward end of which extends to the forward end of the frame adjacent the mast. When 105 the rod 27 is drawn forwardly, the arm 26 110

and shaft 20 assume the positions shown in the dotted lines in Figure 5 causing the bull wheel 22 to come into frictional engagement with the drum 21 and the bull wheel shaft 20 to be rotated. When the arm 26 is moved in the opposite direction, however, the shaft 20 is shifted forwardly and the bull wheel 22 comes into engagement with the brake 23 and the bull wheel shaft is held against movement. When the bull wheel and arm 26 are in the position shown in full lines in Figure 5, the bull wheel is free from engagement with either the brake 23 or friction drum 21, as hereinbefore stated.

15 To the bull wheel shaft 20 is secured one end of a cable 29 which cable passes over the pulley or a sheave 30 mounted upon the upper end of the mast 11, the end of the cable being adapted for attachment to the usual boring tools which are indicated at 31.

To the opposite end of the band wheel shaft from that bearing the band wheel 16, is secured a crank 32 to the end of which is pivotally connected one end of a link 33. 25 The forward end of the link 33 is connected to the end of the crank 34 secured to a shaft 35 hereinafter to be referred to as the spudding shaft. Interiorly of the frame, the shaft 35 is provided with a second arm 36, the free end of which is pivotally connected to a spudding arm 37 provided with a hook adapted to engage the cable 29. The inner end of the shaft 35 is preferably extended beyond the arm 36 and when the 30 spudding shoe 37 is not engaged with the cable 29, the hooked end 38 thereof rests against the shaft preventing the spudding shoe from coming into contact with the ground in a manner which might cause 35 breakage thereto.

To the band wheel shaft 15, adjacent that end thereof bearing the arm 32 but interiorly of the frame, is secured a second friction drum 39 which is preferably likewise 45 provided with a V-shaped friction face. Extending transversely of the frame rearwardly of the band wheel shaft 15, is a sand reel shaft 40 which is provided with a friction wheel 41 adapted to coact with the friction wheel 39. Upon the opposite side of the friction wheel 41 from the friction wheel 39, a brake 42 is secured to the frame 10. The adjacent end of the sand wheel shaft 40 is mounted in the bearing 43 50 which is longitudinally shiftable upon the frame 10. A yoke 44 is provided embodying spaced arms 45 extending upon the opposite sides of one side arm of the frame and pivotally connected thereto, as at 46, the upper ends of the arms being inturned and engaging the bearing 43. To the lower end 55 of the yoke 44 is pivotally connected the rear end of a link 48, the forward end of which is pivotally connected to the end of an arm 49 of a rock shaft 50 extending

transversely of the frame and provided with any suitable means whereby the same may be rocked, as a handle. If the shaft 50 is so rocked as to cause the link 48 to move rearwardly, the bearing 43 is forced forwardly and the sand reel friction drum 41 is forced into engagement with the friction drum 39 by the band wheel shaft 15. If, however, the link 48 is moved forwardly, the friction drum 41 is forced into engagement with the brake 42 and the sand reel shaft 40 held against movement. 75

In the use of my device, when it is desired to drill, the bull wheel shaft is released to permit the weight of the tools to unreel the cable 29 from the bull wheel shaft 20 until the tools arrive at the bottom of the bore. The bull wheel shaft may then be shifted until the bull wheel 22 comes into engagement with the brake 23 and the bull wheel shaft is held against rotation. The spudding shoe 37 is then engaged with the cable 29 by passing the hook end 38 thereof over the cable. If the band wheel shaft is now rotated, this rotation will impart a rocking movement to the shaft 35, arm 36 and to the spudding shoe 37. This rocking movement causes the cable 29 to be alternately drawn to the position shown in solid lines in Figure 2 and released to the position shown in the dotted lines with the result that the boring bar is reciprocated. When it is desired to elevate the tool 31 and clean the bore, the shoe 37 is released from the cable and the operating bar 27 pulled forwardly when the bull wheel will come into engagement with the friction wheel 21 of the band wheel shaft and the bull wheel shaft 20 will be rotated, winding the cable 21 thereon and elevating the tools. 95 When the tool is fully withdrawn the handle is forced inwardly until the bull wheel comes into engagement with the brake 23 thereof when the tool will be held in elevated position. When it is desired to clean the well, the sand bucket 54 may be placed in the bore and the reel released from movement and the weight of the sand bucket will cause the cable 51 to be unreel therefrom until the bucket arrives at the bottom of the bore. 100 When it is desired to elevate the bucket, the shaft 50 is rocked so as to cause the link to move rearwardly and bring the shaft drums 41 and 39 into engagement when the sand wheel shaft will be driven from the band wheel shaft and the cable therefrom wound thereon. 110

115 It will be obvious to those familiar with the art that the accompanying drawings merely diagrammatically illustrate the construction and arrangement of my drilling rig; and it will likewise be obvious that many changes in such construction are possible without in any manner departing from the spirit of my invention. I, accordingly, 120 125 130

do not limit myself to the construction hereinbefore set forth, except as so limited by the subjoined claim.

What I claim is:

- 5 In a well drilling rig, a frame, a mast secured thereon and having a sheave at its upper end, a bull wheel shaft, a cable connected to the bull wheel shaft and passing over the sheave, a bell crank lever, a band 10 wheel shaft, an operating connection between the band wheel shaft and one arm of the bell crank lever and a spudding shoe pivoted to the opposite arm of the bell crank

lever and having a hooked end to engage a portion of the cable between the bull wheel 15 shaft and the sheave, the connection between the arms of the bell crank lever including a shaft pivoted upon the frame, the inner end of the shaft extending inwardly of the arm to which the shoe is connected and forming 20 a support for the free end of the shoe when the same is not in use.

In testimony whereof I hereunto affix my signature.

WILLIAM J. JEFFERS.
